UNITED STATES PATENT OFFICE.

HOWARD H. WIXON, OF CHICAGO, ILLINOIS, ASSIGNOR TO STROMBERG MOTOR DEVICES COMPANY, OF CHICAGO, ILLINOIS, A CORPORATION OF ILLINOIS.

INTERRUPTER FOR IGNITION-DYNAMOS.

1,078,233.

Specification of Letters Patent.

Patented Nov. 11, 1913.

Original application filed March 4, 1910, Serial No. 547,190. Divided and this application filed September 6, 1910. Serial No. 580,717.

To all whom it may concern:

Be it known that I, HOWARD H. WIXON, a citizen of the United States, residing at Chicago, in the county of Cook and State 5 of Illinois, have invented a certain new and useful Improvement in Interrupters for Ignition-DYNAMOS, of which the following is a full, clear, concise, and exact description, reference being had to the accompanying 10 drawings, forming a part of this specification.

My invention relates to ignition dynamos such as are employed in connection with gas engines for automobiles, and is more particularly directed to interrupter mechanism therefor.

This case is divisional from my copending application, Serial No. 547,190, filed March 4, 1910, wherein a magneto ignition device is 20 shown and described.

In this type of machine, and in the system employed in connection therewith, inductively related high and low tension circuits are employed and, in operation, it is 25 necessary that the primary circuit be interrupted intermittently so that the high tension current will jump the gap in the secondary circuit, physically disposed in the engine cylinder.

30 The novel features of my invention lie in the construction of the interrupter whereby the circuit controlled thereby is interrupted first by one pair of contacts and then by another, in order to distribute the injurious 35 effect of the sparking among the several contacts, the life of the interrupter contacts being thereby greatly prolonged.

The novel features of my invention reside further in the arrangement of the interrupter contacts in the ignition system, this 40 improved arrangement being peculiarly related to the construction above pointed out.

45 My invention is embodied in the device illustrated in the accompanying drawings, in which—

Figure 1 is an end elevational view of the magneto; Fig. 2 is a longitudinal sectional view taken on the plane indicated by the line 2, 2 of Fig. 1 and looking in the direction indicated in the drawings; Fig. 3 is 50 an isolated cross-sectional view taken on the plane indicated by the line 3, 3 of Fig. 1 and looking in the direction indicated by the arrows, showing the interrupter cas-

ing in position on the magneto; Fig. 4 is an 55 interior elevational view of the interrupter; and Fig. 5 is a diagram of the circuit connections.

Like reference characters are applied to the same parts throughout the various figures.

The main framework of the machine comprises the non-magnetic base portion 1, a pair of magnetic side portions 2, a non-magnetic top portion 3, and supporting end 65 plates 4 and 5, all held together in some suitable manner, for instance by means of the screws 6, 6. The permanent magnets 7, 7 are in good magnetic contact with the side pieces 2 and, extending upwardly, embrace some of the working parts of the machine, as is usual in the art.

In the particular machine herein shown, the space between the magnetic side pieces 75 is occupied by a stationary induction winding 8 comprising the inner or primary coil 9 and the outer or secondary coil 10. Upon the outside of the winding are located the terminals which are intended to engage certain contact members, as will be described 80 subsequently, mounted at certain points on the machine.

Passing axially through the winding is the armature shaft 11 rotatably supported in bearings 12 and 13. The bearing 12 is 85 carried in the supplemental end plate 14, which is secured to the end plate 4 and to the framework of the machine, while the bearing 13 is mounted in the support 15 held in the other end plate 5. Antifriction rollers 16 work in the bearings 12 and 13, as is clearly shown in the drawings. A pair of segmental polar extensions 17 and 18 are secured to the armature shaft at opposite 95 ends of the winding, first by means of the screw threads on the armature shaft and second by means of the set screws 19, 19. The polar extensions as well as the armature shaft—at least that portion of the armature shaft which is included between the polar 100 extensions—are of magnetic material, and it will be seen therefore that the armature shaft constitutes a rotatable magnetic core for the stationary induction winding. The angular position of the polar extensions 17 and 18 on the armature shaft is such that they lie substantially diametrically opposite, 105 as indicated in Fig. 2, and in order to pro-

vide a large surface on the faces of these polar extensions, I have preferably formed the extensions with elongations 20, 20 projecting into the space between the winding 5 and the framework. It will appear to those skilled in the art that as the armature is rotated or oscillated the magnetic flux of the field will be periodically short-circuited through the winding, first in one direction 10 and then in the reverse direction, and that this will set up an electromotive force in the winding by the action of the field magnet. If the primary coil is short-circuited, the current flowing therethrough generates 15 lines of magnetic force which largely neutralize the existing magnetic field—that is, they force back or oppose a change of magnetism through the coil. As soon as the circuit in the primary winding is broken, the 20 counteraction of the generated opposing flux ceases. Owing to the change which thereby instantaneously arises in the number of lines of force passing through the secondary coil from the field magnets, the 25 potential rises so high in the secondary coil that a spark is produced across the contacts of the spark plug to ignite the explosive mixture in the engine cylinder. The wire in the primary coil is comparatively coarse 30 and comprises comparatively few turns, while the wire constituting the secondary coil is comparatively fine and comprises a comparatively large number of turns, in order that the electromotive force generated 35 in the secondary coil may be sufficiently high to cause sparking at the spark plugs of the engine cylinders.

Referring now to the improved interrupter of my invention, it will be seen that 40 the armature shaft 11 has an extension 21 to which is rigidly secured the yoke 22, having at its opposite ends a pair of rollers 23 and 24 pivoted at 25 and 26, respectively. These rollers are insulated from the arm by 45 insulating bushings 27 and 28, as clearly shown in Fig. 2. The yoke 22 with its oppositely disposed engaging surfaces, shown as rollers in the specific embodiment illustrated, constitutes the movable contact member of 50 the interrupter of my invention. Just how this contact member co-operates with the circuit contacts of the interrupter is best illustrated in Fig. 4, which shows the various parts that go to make up the mechanism. 55 To the cylindrical support 29 are secured the movable spring contacts 30 and 31, which co-operate with the stationary contacts 32 and 33, respectively. Springs 34 and 35 hold the movable contacts 30 and 31 in firm engagement 60 with their respective stationary contacts, although the resiliency of the movable contacts may be made sufficiently strong to dispense with the auxiliary springs. The cylindrical support 29 is of good conducting 65 metal, such as brass, and the movable contacts

30 and 31 are electrically connected with this support. The stationary contacts 32 and 33 are carried by metallic studs 36 and 37, respectively, which studs find bearing in the outer metallic plate 38. This outer plate constitutes a cover for the cylindrical support 29 and these two parts may be said to constitute a cylindrical casing. An insulating disk 39 entirely insulates the cylindrical support 29 from the cover plate 70 75 38, with the result that the movable contacts 30 and 31 and their respectively fixed contacts 32 and 33 are electrically connected in parallel.

It will be apparent from Fig. 4 that the rollers 23 and 24 of the interrupter yoke are of unequal size, so that the oppositely disposed engaging surfaces of the yoke may be said to be at unequal distances from the axis of rotation. The purpose of this arrangement is to cause the interruption of the primary circuit, in which the interrupter is included, first by one pair of contacts and then by the other, in order that the burden of sparking may be distributed between the 80 85 two pairs of contacts. It is clear that in this way the life of the contacts is practically doubled, and the interrupter will endure substantially twice as long as it would if there were but a single pair of contacts for 90 interrupting the primary circuit. If we assume the rotation of the interrupter arm as indicated by the arrow in Fig. 4, it will be seen that the contacts 30 and 32 will be separated first. However, this will cause no interruption of the primary circuit, for the reason that the circuit is still closed through the parallel path which includes the other pair of contacts, namely, the contacts 31 and 33. As the arm continues its rotation, the roller 24 will come into engagement with the movable contact 31 and separate the same from the stationary contact 33, while the other pair of contacts is still held separated by the roller 23. This separation of the contacts 31 and 33 interrupts the primary circuit, thereby causing the induction of a high electromotive force in the secondary circuit to fire the charge in the proper engine cylinder. As the yoke 22 continues its rotation, the roller 24 will be the first to release its associated movable contact, and the circuit will be closed, almost instantaneously after its interruption through the contacts 31 and 33. These will be followed in quick succession by the closure of the parallel path which includes the other pair of contacts 30 and 32. When the interrupter arm reaches a position 180 degrees from that shown in Fig. 4, it will be clear that the larger roller 100 105 110 115 120 125 130 23 will first open the parallel path which includes the contacts 31 and 33. However, this will not interrupt the primary circuit, because the circuit is still closed through the parallel path which includes the contacts 30

and 32. As soon as the smaller roller 24 separates the contact 30 from the contact 32 (which will, of course, take place while the contacts 31 and 33 are held separated by the roller 23), the primary circuit will again be interrupted and whatever sparking will take place at this moment of interruption will be across the contacts 30 and 33. By thus causing interruption of the primary circuit, first through one pair of contacts and then through the other, the life of the interrupter is practically double that of those interrupters in which but a single pair of contacts is employed. And this advantage is secured by so arranging the two pairs of contacts and the interrupter yoke that the cyclical actuation of the contacts takes place in succession, the circuit being interrupted alternately by one pair of contacts 20 and then the other pair.

In order that the interrupter casing may be readily attached to the magneto and as readily removed therefrom, a bearing plate 40 is rotatably mounted in the end plate 5, 25 as shown in Fig. 2. Through the opening 41 in this bearing plate passes the extension 21 of the armature shaft. This rotatable bearing plate carries two oppositely disposed studs 42 and 43 screwed thereinto. 30 These studs are provided with head portions 44 and 45, respectively, and with insulating sleeves 46 and 47, respectively. The cylindrical support 29 is provided with two oppositely arranged enlargements or bosses 48 35 provided with openings 49. The cover piece 38 carries a cross bar 50. A pair of openings 51 extend through the cover piece and the bar 50 in alinement with the openings 49, as best shown in Fig. 3. Into the 40 openings 51 extend the projections or buttons 52, which are pressed outwardly by suitable springs 53. When it is desired to insert the interrupter casing in place in the magneto, it is necessary only to bring the 45 openings of the casing into alinement with the studs 42 and 43 and to press the casing inwardly until the parts are in the position shown in Fig. 3, when the buttons 52 will rest in the grooves of the head portions 44 and 45 of the studs 42 and 43. This 50 produces a separable locking engagement between the rotatable base plate 40 and the interrupter casing.

As shown in Figs. 2 and 3, the end plate 5 55 is provided with a circular shoulder 54, which forms a housing for the interrupter casing. An insulating disk 55, preferably secured to the base plate 40, insulates the latter from the cylindrical support 29 of 60 the interrupter casing. From this it will be seen that the stationary contacts 32 and 33 are grounded to the magneto, while the movable contacts 30 and 31 are insulated therefrom. The binding post 56 is carried by 65 the end plate 5 and insulated therefrom by

an insulating bushing 57, as shown in Fig. 3. This binding post makes electrical contact with the cylindrical support 29, and therefore with the movable contacts 30 and 31 carried by said support. This is diagrammatically shown in Fig. 5, which also shows the stationary contacts 32 and 33 grounded to the machine at G. The detail description of this figure will be taken up later on in due course. The object of having the interrupter radially adjustable is to vary the moment of sparking with respect to the position of the engine piston. Since the armature shaft is driven by the engine, and since the interrupter yoke 22 is driven 70 by the armature, it will be apparent that by rotating the interrupter casing, the moment at which the circuit will be interrupted by one of the pairs of contacts may be varied with respect to the position of the engine 75 piston, or (which amounts to the same thing) with respect to the position of the armature. In order to get the best sparking it is customary to so time the moment of circuit interruption that it will occur 80 substantially at the moment of generation of maximum electromotive force, which (as is well known) takes place when the armature is about to interrupt the magnetic short-circuit through the induction winding, or at 85 least reduce it to a minimum. In my magneto this will take place when the armature is substantially in the position in which it is shown in Fig. 2, or in a position 180 degrees therefrom. In order to facilitate 90 the adjustment of the interrupter casing I have provided an arm 58, arranged at right angles to the bar 50 and removably attached to the interrupter casing in any suitable manner. In the present instance the cover 100 plate 38 of the interrupter casing carries a pair of studs 59, which enter openings 60 in the arm 58, the spring-pressed buttons 61 providing a separable locking engagement between the two parts. The arm 58 105 has an extension 62 provided with an opening 63 to afford connection with the time lever of the automobile equipment, or with some other suitable part which the driver of the machine may conveniently operate to 110 adjust the time of ignition.

In order that the device of my invention may be adapted to use with multi-cylinder engines, it is necessary that a "distributer" be employed. For the sake of illustration, 115 it has been assumed that the precise embodiment of the magneto illustrated in the accompanying drawings is for a four-cylinder engine and therefore the distributer is shown as provided with four contacts in 120 Fig. 5. The distributer illustrated in Figs. 1 and 2 of the drawings comprises the subject matter of my copending application, Serial No. 580,718, filed of even date here-with, and it will therefore be unnecessary 125

in the present connection to describe its construction in detail. Suffice it to say that a plurality of contacts are stationarily mounted in the insulating casing 64, secured to the end plate 5 by means of screws 65, 65. The contacts are individually connected with the respective spark plugs by means of the leads 66, 66. An auxiliary shaft 67 is mounted in the bearings 68 and 69, set in the end plates 4 and 5, respectively, anti-friction balls 70, 70 being provided, and carries the gear 71 incased between the end plate 4 and the supplementary end plate 14. This gear meshes with pinion 72 secured upon the main shaft 11. The auxiliary shaft 67, beyond the bearing 69, carries the insulating block 73 which operates in a circular pocket 74 in the casing 64, this pocket being covered by a mica plate 75. The insulating block 73 carries the contact member 76 which is adapted to contact successively with the rotary contacts, all as shown in detail and described in my copending application, Serial No. 580,718. The insulating block 73 also carries a spark electrode 77 which is spaced from a metallic point 78 of the auxiliary shaft to form a spark gap which is described in my copending application just referred to as a "combined safety and testing spark gap." The auxiliary shaft 67 is provided with a central insulating portion 79 and the parts just referred to more or less broadly are so interconnected and insulated and so associated with the windings 9 and 10 that the circuit arrangement of Fig. 5 may be maintained. A condenser 80 is conveniently supported within the magneto on top of the member 3.

Referring to Fig. 5, it will be seen that the primary winding 9 is connected between ground and the movable contacts of the interrupter, while the stationary contacts of the interrupter are connected back to ground. It will also be noted that the condenser 80 is connected in shunt of the interrupter and that the secondary winding 10 is connected between ground and the movable member of the distributor, while the stationary contacts of the distributor are connected through the spark plugs back to ground. The spark electrode 77 of the safety and test gap arrangement is shown in close proximity to the metallic plate 78, connected with the movable member 76 of the distributor, and is further shown as electrically connected with ground. Here again it may well be pointed out that the pairs of interrupter contacts are connected in parallel, the condenser being also parallel therewith to prevent as much as possible the sparking at the electrodes which interrupt the primary circuit and also to increase the voltage in the secondary circuit by accelerating the flux variations through the induction winding. If the sparking is too early or too

late, the interrupter may readily be adjusted in the manner previously described.

It is evident that the interrupter of my invention may be employed in connection with other physical arrangements than that herein precisely shown and with other circuit arrangements than that shown in Fig. 5, and I therefore wish the appended claims to be viewed in this broad way.

I claim as new and desire to secure by Letters Patent:

1. An interrupter for magneto generators comprising, in combination, a support, two pairs of normally closed contacts carried by said support, one contact of each pair being fixed and the other movable, and a rotatable member having oppositely disposed engaging surfaces for actuating said movable contacts respectively to open them one after the other in quick succession. 85

2. An interrupter for magneto generators comprising, in combination, a casing, two pairs of normally closed contacts symmetrically mounted in said casing, one contact of each pair being fixed and the other movable, and a rotatable arm associated with said contacts, said arm being pivoted intermediate between its ends and provided with engaging surfaces disposed at different distances from the axis of rotation for actuating said movable contacts one after the other in quick succession. 95

3. An interrupter for magneto generators comprising, in combination, a casing, two pairs of normally closed contacts symmetrically mounted in said casing, one contact of each pair being fixed and the other movable, and a rotatable arm associated with said contacts, said arm being pivoted intermediate between its ends and provided with rollers of different size for actuating said movable contacts one after the other in quick succession. 100

4. In an ignition system, a circuit provided with two pairs of interrupter contacts connected in parallel, and means for actuating said contacts simultaneously but to open in quick succession to cyclically interrupt the circuit, first by one pair of contacts and then by the other. 110

5. In an ignition system, a circuit provided with a plurality of interrupter switches connected in parallel, and means for actuating said switches at different intervals to cause cyclical interruptions of the circuit by said switches in succession and closure in the reverse order. 120

6. An interrupter for magneto generators comprising, in combination, movable contacts, stationary contacts, and means for operating the movable contacts at the same time but separating the different pairs of contacts at different times. 125

7. An interrupter for magneto generators comprising, in combination, stationary con- 130

tacts, movable contacts, and means for operating the movable contacts at the same time but regularly separating the different pairs of contacts at different times.

5 8. In a magneto generator, a supporting member, studs extending therefrom, an interrupter casing mounted upon said studs, and resilient means for engaging said studs beyond the casing to hold said interrupter

10 using in place.

9. In a magneto generator, a cylindrical supporting shell, an auxiliary supporting member disposed inside but insulated from said shell, contacts carried by said auxiliary

15 supporting member, a cover mounted upon said shell and rotatable relative thereto, the auxiliary supporting member being rotatable therewith but insulated therefrom and contacts carried by said cover for association

20 with said first-named contacts.

10. In a magneto generator, a cylindrical supporting shell, an auxiliary supporting member disposed inside but insulated from said shell, contacts carried by said auxiliary

25 supporting member, a cover mounted upon said shell and rotatable relative thereto, the auxiliary supporting member being rotatable therewith but insulated therefrom, contacts carried by said cover for association

30 with said first-named contacts, and an adjusting arm positively connected with said cover and resiliently held in place.

11. In a magneto generator, in combination, a supporting member, a rotatable plate

35 mounted in said supporting member, studs carried by said plate, a cover carried by said

studs, an auxiliary supporting member clamped between but insulated from said plate and cover, contacts carried by said last-named supporting member, contacts 40 carried by said cover, and means for periodically actuating said contacts.

12. In a magneto generator, in combination, a supporting member, a rotatable plate mounted in said supporting member, studs 45 carried by said plate, a cover carried by

said studs, an auxiliary supporting member clamped between but insulated from said plate and cover, contacts carried by said last-named supporting member, contacts 50 carried by said cover, means for periodically actuating said contacts, and a binding post mounted in but insulated from said first-named supporting member and having connection with said second named supporting member.

13. In an interrupter for magneto ignition devices, a pair of movable contacts, a pair of stationary contacts respectively associated therewith, a rotatable yoke centrally pivoted relative to said contacts, and rollers pivoted on said yoke equidistant from the center for periodic engagement with said movable contacts, one of said rollers being larger than the other. 65

In witness whereof, I hereunto subscribe my name this 3rd day of September, A. D. 1910.

HOWARD H. WIXON.
